11 Claims. (Cl. 250—6)

1

This invention relates to communication systems, and more particularly to systems of the variable dot type, and has for its primary object to provide an improved variable dot signalling system.

Heretofore, dots of variable lengths and constant repetition frequency were produced from a signal wave by starting and stopping the dot at instants when the sum of the modulation signal and a triangular auxiliary wave was zero. This resulted in a train of variable dots from which it was difficult to reconstruct accurately the original signal.

According to the present invention, sequence switching of capacitance storage devices permit dot length to represent actual signal value at selected uniformly timed instants so that similar devices at the receiver may construct a rectilinear wave closely representative of the original signal. If it is preferred, the dot length may be made to represent an average signal value over periodically recurring and successive selected periods.

Another object of this invention is to provide a variable dot signal more nearly a correct representation of an original signal.

Still another object of this invention is to provide a system to reconvert a variable dot signal into an original signal wave more nearly a true representation of the original signal.

Other and incidental objects of the invention will be apparent to those skilled in the art from the following specification considered in connection with the accompanying drawings, in which,

Figure 1 is a circuit diagram showing one form of this invention in which signal waves are converted into modulated dots whose duration depends upon the instantaneous value of the original signal waves at predetermined reoccurring instants,

Figure 2 is a circuit diagram showing one form of this invention for reconstructing an original signal wave from a modulated dot signal,

Figure 3 is a graphical illustration of the derivation from a signal wave of the variable dot signal whose dot duration depends upon the instantaneous value of the amplitude-modulated signal, in accordance with the form of this invention shown in Figure 1,

Figure 4 is a graphical illustration of the reconstruction of the original signal waves from a modulated dot signal, in accordance with one form of this invention, as illustrated by the circuit diagram in Figure 2,

Figure 5 is a graphical illustration of the con-

2 version of signal trains to variable dot signals, in accordance with the prior art,

Figure 6 is also a graphical illustration of the reconstruction of a signal from the variable dot train, in accordance with the prior art,

Figure 7 is a circuit diagram showing another form of this invention for converting a signal wave into a dot signal, the length of the dots depending upon the average value of the signal during a predetermined recurring interval of time,

Figure 8 is a graphical illustration of the production of a variable dot train from a signal train, in accordance with the form of the invention shown by the circuit diagram in Fig. 7,

Figure 9 shows a circuit diagram of another form of this invention for reconverting modulated dots into a signal wave.

Figure 10 is a graphical illustration of the reproduction of a signal wave from a variable dot train, in accordance with the form of this invention as described in the circuit diagram of Fig. 9, and

Fig. 11 is a circuit diagram showing one form of this invention employing electronic switching means for converting a signal wave into a modulated dot train.

Fig. 5 shows curve *a* which results from superimposing an auxiliary saw-tooth wave train shown dotted as *b* having a frequency, for example, of 30,000 per second on a signal *c* such as, for example, a sine wave signal of 8000 cycles per second and having an amplitude $\frac{1}{2}$ of the saw-tooth wave amplitude.

It will be seen that, with such severe modulation, portions of the originally rectilinear auxiliary wave become distinctly curved. It is the information contained in this curvature that is lost in a variable dot type of transmission by the use of methods and means known to the prior art.

The light and dark segments of the zero line indicate the off and on dot elements produced by limiting this wave to the neighborhood of zero, one well known method of producing modulated dots.

It is clear that reproduction from these dots which indicate nothing but crossing of the zero line by the composite wave can never be exact.

Fig. 6 shows a train of variable dots derived from the sine wave in Fig. 5 by a method and means of the prior art such as briefly described above.

This shows clearly the small resemblance between the variable dot train and the original signal.

Among the systems of the prior art, there is no

generally accepted method of reconstructing the original signal from such a train of modulated dots. It is, however, obvious that when so few dots per cycle of the signal wave as shown in Figs. 5 and 6 are transmitted, much of the information in the original wave is necessarily lost and any reconstructed wave must be appreciably distorted. The rather complex relation between the dot starting instants of the prior art system, represented by Fig. 5, and the original signal wave enhances the difficulty of keeping down the distortion of a reconstructed signal wave.

The transmission of relatively few dots per modulating cycle causes distortion and it is therefore preferable that more dots per modulating cycle be transmitted. Since the use of sharp edged dots is obviously necessary to the noise suppressing function of the systems, harmonics of the dot frequency must be transmitted, and for dots of radio frequency energy each of these harmonics yields a pair of side bands. For retention of a reasonable band width, it is obviously necessary to reduce the number of dots transmitted per modulated cycle as far as possible. Thus for a given degree of noise suppression, the dot repetition frequency chosen must be the result of a compromise between fidelity and band width. In practice, the quality of reproduction obtained with only three or four dots per cycle of maximum modulation frequency is surprisingly good.

If only impulses marking the starting and stopping instants of the dots are to be transmitted, the frequency band required, of course, becomes very much greater.

By the use of sequence switches to charge and discharge condensers, it is possible to control dot duration in accordance with the magnitude of the signal at the instant of stopping of the preceding dot. Transmission of this type supplies information about the actual modulation values at regularly timed selected instants. From this dot signal, complicated, but realizable, switching arrangements permit a rectilinear wave having the same values as the original modulation at the chosen dot cessation instants to be constructed.

Fig. 1 is a circuit of a system employing mechanical switching means. It is well known that a capacitor connected across a low resistance load in a vacuum tube plate circuit will always be charged with a voltage proportional to the instantaneous value of the signal input to the tube. If disconnected from the tube and discharged through a constant current device, the time taken to reach a fixed reference voltage is proportional to the value of the input signal at the instant of disconnection.

A signal wave is applied to the input circuit of a low impedance vacuum tube 1 whose plate current is supplied through a resistor 3. A synchronous motor 5 drives the commutator including capacitors 7e and 7f. The speed of the synchronous motor 5 will be determined by the repetition frequency of the desired modulated dot signal.

In the position of the commutator shown, the condenser 7e receives a charge which amount is proportional to the magnitude of the incoming signal wave at the instant the condenser 7e is disconnected from the charging circuit. As the commutator revolves in a counterclockwise direction, as shown by the arrow, condenser 7e moves to the discharge position and discharges through a constant current device shown, for example, as a saturated diode 9. It will be noticed that the condenser is inverted in its discharge

position such that the potential on the cathode of the diode 9 is negative with respect to ground.

As the condenser 7e is discharged through a constant current device 9, condenser 7f is assuming its charge.

The voltage across the constant current device 9 is impressed upon the gas tube 11 through a second commutator 13 connecting terminals 15 and 17. The voltage charge on the condenser 7e leaks off through the constant current device 9 such as to cause the control electrode of the gas tube 11 to gradually become less negative. When the potential on the control electrode of the gas tube 11 reaches the igniting voltage, the tube 11 will ignite and pass current until the plate circuit of tube 11 is opened by commutator 18.

During the interval in which the commutator 13 connects the segment 17 to the segment 15, such as to connect the gas tube 11 in the circuit, a third commutator 19 connects the plate 14 of the gas tube 11 to the output circuit which contains a resistor 19 connected to a voltage source.

While the tube 11 is conducting, the voltage across the output terminals 20 will be small, because of the voltage drop across the resistor 19.

Thus it will be seen that the output voltage will remain high for a period of time depending directly upon the voltage charge of condenser 7e, or an amount which varies in direct proportion to the magnitude of the incoming signal wave.

Obviously uniform repetition of the entire cycle by using two storage capacitors 7e and 7f, gas triodes 11 and 12 alternately will give a modulated dot train with dots ending at uniformly spaced instants and having durations proportional to the values of the signal at predetermined instants. It is necessary to provide at least two gas triodes 11 and 12 because of a physical characteristic of a gas triode in which it is absolutely necessary that the tube be completely extinguished before being reignited. In the case of high percentage modulation, the period allowed for extinguishing the gas tube will be very small and in order to insure proper operation, a pair of gas tubes is employed alternately. A single vacuum tube may be employed in place of the gas tubes which makes it necessary to have only one tube to perform this step as it requires no time to be made non-conducting.

Figure 3 is a graphical illustration of the operation of the circuit shown in Fig. 1. For the purpose of illustration, a sine wave is used and a dot repetition frequency equal to that illustrated in Figs. 5 and 6 is also used. The dotted curve e represents the potential on the condenser 7e of Fig. 1. It will be seen that during the interval of time t_1 , t_2 , condenser 7e is receiving a charge and at t_2 , when it is disconnected from the charging circuit, its charged potential is equal to the instantaneous potential of the incoming signal at the time t_2 . Immediately upon being disconnected, it is connected to the discharging circuit through the constant current device such that its potential decreases uniformly as shown by the uniformly sloping dotted curve e between t_2 and t_3 . As previously explained, as this charged potential on condenser 7e drops in a positive direction to the igniting voltage of the gas tube 11, a current flows through the gas tube 11 which causes a cessation of the modulated dot, which is shown in a heavy line below the dotted curve e and extends from the instant t_2 , at which commutators 13 and 18 connect tube 11 in circuit, until the dotted curve e arrives at a predetermined level.

During the interval of time t_2 to t_3 , condenser $1f$ is receiving its charge, and at time t_3 it is disconnected, at which time its charge is equal to the instantaneous value of the incoming signal at time t_3 . Likewise, condenser $1f$ is allowed to discharge through the constant current device 9 such that a potential across the condenser $1f$ decreases from a highly negative potential to the predetermined reference voltage which ignites the gas tube 12 such as to terminate a second modulated dot shown as the heavy line below the dashed line f in Fig. 3. The off time of the modulated dot determined by the charge on condenser $1f$ is represented graphically by the extension of the dashed curve f and continues until time t_4 when tube 12 is disconnected and condenser $1f$ is returned to the charging position, and the cycle is repeated.

Fig. 2 shows one form of this invention for re-converting modulated dots into an approximate replica of the original signal wave. In the reconstruction process, it is necessary to derive, from the successive dot durations, voltages corresponding to instantaneous values of the desired replica wave at the instants of dot starting and then to connect these instantaneous values into a continuous signal by rectilinear wave segments.

If a capacitor is connected across the output circuit of a constant current device such as a pentode amplifier tube it will be charged with an amount of energy just proportional to the duration of the constant charging signal. A replica signal is thus produced from a modulated dot signal and is representative of the original dot modulating signal. This may be accomplished by charging a capacitor with a constant current proportional to the length of one dot and simultaneously discharging it with a constant current proportional to the length of the preceding dot. Dot lengths may determine constant voltages, for controlling the above mentioned constant currents, by controlling duration of constant charging current into an auxiliary capacitor. The sequence of operations consists of four parts, each lasting for one dot and each requiring one auxiliary condenser. First, such an auxiliary capacitor is charged under dot control. Secondly, it is used to control charging current to an integrating capacitor. Third, it controls discharge currents from the integrating capacitor and fourth, it is discharged prior to repeating the cycle.

This series of operations may be produced by the circuits shown in Fig. 2. An input signal of modulated dots is applied to the constant current device 21 with such a polarity that the dot causes this device to pass current. A synchronous motor 23 drives a commutator including condensers $25g$, $25h$, $25i$ and $25j$. For the purpose of simplifying the explanation, condenser $25g$ and its associated connection are drawn in heavy lines. In the position shown condenser $25g$ receives its charge during the dot portion of the interval during which the condenser $25g$ is connected in the output circuit of the constant current device 21 . It will be noticed that there is no direct current connection between the source of potential and the anode of the tube 21 but it will be remembered that the storing of energy in condensers which are being periodically charged may supply anode current for the discharge device 21 . It will thus be seen that the series connection of condenser $25g$ in the plate circuit will cause it to have a charge whose voltage will be proportional to the duration of that dot portion of the time

interval in which condenser $25g$ is connected in the plate circuit of the tube 21 . This position of the condenser $25g$ is represented by I.

As all the condensers, including condenser $25g$, move to the second position such that condenser $25g$ is in position II the energy stored therein is used to control the charging current to the integrating capacitor 33 through a constant current device 35 by causing its control electrode 36 to be maintained at a potential which amount is proportional to the amount of the charge received in the position I of condenser $25g$. This potential remains substantially constant during one complete dot interval.

It will be noted that the discharge device 35 is connected in series with a second constant current device 37 . During the complete dot interval in which condenser $25g$ is in position II for maintaining the control electrode 36 of tube 35 at a constant potential depending upon its previously received charge, condenser $25j$ has advanced to position III and its charge which was accumulated while it was in position I causes the control electrode 38 of tube 37 to be maintained at a potential which is proportional to the amount of charge condenser $25j$ received while in its charging position I.

It will be seen that the resulting potential across the integrating capacitor 33 is an amount which is controlled by the current flowing through both tubes 35 and 37 . It therefore follows that the potential across the condenser 33 varies linearly between values proportional to the instantaneous values of the original signal at the instants of dot starting.

As the set of condensers including condenser $25g$ moves to their next position, such that condenser $25g$ is in position III, the charge on condenser $25g$ controls the potential on the control electrode 38 of tube 37 , while the condenser $25h$ is controlling the potential on the control electrode 36 of the tube 35 . During this interval condenser $25i$ is receiving its charge.

In the fourth position, that is such that condenser $25g$ is in position IV, the charge on the condenser $25g$ is allowed to leak off through a short circuit and in the next position the complete cycle is repeated.

It will be seen that each of the condensers $25g$, $25h$, $25i$ and $25j$ will follow these operations sequentially so that continuous operation results and the output across the integrating capacitor 33 is a signal wave whose instantaneous amplitudes at successive dot starting instants are respectively proportional to the durations of the successive incoming modulated dots.

Fig. 4 illustrates graphically the operation of the previously described form of this invention under Fig. 2. For the purpose of facilitating explanation the curves in Fig. 4 are given letters corresponding to the letters of the condensers in Fig. 2. The curves illustrate the potential on each condenser during the complete cycle. The input signal of modulated dots is represented by the heavy variable dots slightly below the zero axis.

During the interval t_2 , t_3 , condenser $25g$ is in position I and receiving its charge through the constant current device 21 during the dot portion of the interval t_2 , t_3 . This is indicated by curve g which during the dot interval is increasingly uniform until the time at which the dot stops. After the dot signal stops between t_2 and t_3 , it will be noticed that the g curve maintains

a uniform amplitude until time t_4 and represents the voltage of condenser $25g$. It will be seen that the charge produced on the condenser $25j$ during the no signal period, t_1, t_2 , while condenser $25j$ was in position I is carried over to the time interval t_3, t_4 . During the time interval t_3, t_4 , condenser $25g$ is in position II as shown in the accompanying chart wherein it is controlling the potential on the control electrode 26 of the tube 35 . During this same interval of time t_3, t_4 , condenser $25j$ is controlling the potential on the control electrode 38 of the tube 37 . It, therefore, follows that the potential across the integrating capacitor 33 will change linearly from the potential representative of or proportional to the potential across the condenser $25j$, which is in turn proportional to the value of the original signal wave at instant t_1 , to that potential representative of the potential across condenser $25g$, which is proportional to the value of the original signal at instant t_2 . This causes the output reconstructed signal to take the form of the heavy curve of Fig. 4.

At time t_4 the potential across condenser $25j$ is shorted out because as previously described position IV is the shorting position. Therefore, the dotted curve j will decrease rapidly to zero as shown in Fig. 4.

Fig. 7 shows a closely related type of converter using a somewhat simpler variable dot transmitter. Instead of transmitting instantaneous signal values at instants beginning each dot period and joining these values by straight lines at the reconverter, it is possible to transmit average signal values over the dot period and maintain these values over the dot period at the reconverter to give a stepped rectangular approximation of the signal wave. On the converter, averaging may be accomplished by using a constant current single tube plate current to charge the capacitor; the cycle becomes a three-part one, and in addition to the charge and discharge of the capacitor, a position for short circuiting or completely discharging the capacitor is also required on the sequence switch.

The receiver cycle is also a three-part cycle, using three capacitors cyclically—one on charge, one supplying output signal voltage (no current), and one on discharge, short circuit.

According to the form of this invention shown in Fig. 7, there is shown one form of this invention in which the average amplitude of the incoming amplitude modulated signal is used to charge a condenser to be later discharged. A signal wave is applied to the constant current discharge device 39 . A synchronous motor 43 drives a commutator including capacitors $45k, 45l$ and $45m$. While condenser $45k$ is in position I, it is receiving a charge which is proportional to the time integral of the voltage impressed upon the discharge device 39 by the signal wave during the corresponding dot period. This charge results from the series connection of the condenser $45k$ from the voltage source supplying the anode current of tube 39 . At the end of this dot period, the accumulated charge on condenser $45k$ is proportional to the time average of the signaling wave during the period.

As the condensers rotate so that condenser $45k$ is in position II, it is discharged through a constant current device which takes the form of a saturated diode 51 .

A second commutator also driven by the synchronous motor 43 includes a common segment 53 connected to the cathode of the constant cur-

rent device 51 and a segment 55 connected to the control electrode of the gas discharge tube 57 .

In position II, the charge in condenser $45k$ is applied to the control electrode of the gas discharge device 57 . At the beginning of the dot period, the charge across the condenser $45k$ is large enough that the resulting negative charge on the control electrode of the gas tube 57 prevents its igniting. This original charge is gradually leaking off the condenser $45k$ so that when the potential across the condenser $45k$ reaches the tube igniting voltage, current flows through the tube 57 for the remainder of the dot period at which time the tube 57 is disconnected from its source of anode voltage which is fed to the commutator 58 and through resistor 59 . This causes tube 57 to be extinguished. There results a variable dot whose length is proportional to the average value of the signal wave during the dot period.

As the condensers rotate to their next position such that condenser $45k$ is in position III, the remaining charge on the condenser $45k$ is allowed to discharge because of being short circuited. The cycle then repeats itself.

It will be noted that three condensers are used such that during each dot period there is one condenser on charge and a different condenser on discharge, and still another condenser on short circuit, so that continuous operation results. There is also provided two additional gaseous discharge devices 61 and 63 which are connected to their respective segments 65 and 67 on the commutator such that each of the gas discharge devices $57, 61$, and 63 operate only one-third of the time and are so connected to the commutator that they operate sequentially.

Fig. 8 shows graphically the operation of the form of this invention as set forth in Fig. 7. The letters representative of the storage condensers in Fig. 7 are used in each of the curves in Fig. 8 to facilitate the explanation of the operation, and the curves in Fig. 7 are representative of the potentials across the storage condensers. The dashed line k represents the voltage of the condenser $45k$, the dotted line l represents the voltage on the condenser $45l$, and the dash-dot line m represents the voltage on the condenser $45m$. A sine wave is used and is divided up into dot intervals similar to those used in previous explanations of other forms of this invention.

During the interval t_1, t_2 , the condenser $45k$ is in position I and is assuming a charge which is proportional to the average amplitude of the incoming amplitude modulated signal during the time interval t_1, t_2 . At time t_2 , the commutator has rotated such as to place condenser $45k$ in position II at which time it starts to discharge through the constant current device 51 . This accounts for the uniform decline taken by curve k starting at t_2 . When the potential on the condenser $45k$ decreases to the potential at which the gas tube will ignite, a cessation of the variable dot occurs, the length of the variable dot, as previously described, continuing from the instant t_2 until the ignition of the tube 57 . The condenser $45k$ continues along the base line between time interval t_3 and t_4 during which time condenser $45k$ is in position III, or discharge position. At time t_4 , condenser $45k$ is again in the charging position, or position I and assumes its charge at a rate proportional to the area under the signal wave or to an amount which at t_5 is in turn proportional to the average amplitude of the signal wave during period t_4 to t_5 .

It will be seen that each of the condensers operate in a similar manner and sequentially such that they produce the desired variable dot signal.

Fig. 9 shows a reconverter circuit to reconvert the variable dot train into a replica of a signal wave whose average amplitude during one dot period is proportional to the dot length. The modulated dot train is applied to the control electrode 64 of a constant current discharge device 65. The output circuit also includes a commutator driven by a synchronous motor 69. The commutator includes capacitors 71p, 71q and 71r. As the condensers are in such a position that condenser 71p is in position I, the condenser 71p is receiving a charge whose stored energy will be proportional to the signal portion of a dot interval.

As the condensers rotate such that condenser 71p is in position II, the condenser 71p will maintain across the output a voltage corresponding to the charge which it has accumulated. The output signal will therefore have a magnitude proportional to the length of the dot which charged the condenser 71p when it was in the first position I.

As the condensers further rotate such that condenser 71p is in position III, the condenser 71p is short circuited such that the remaining energy therein is discharged. Therefore, when it returns to the charging position, the voltage produced across it is directly proportional to the charge which it accumulates.

Condensers 71q and 71r pass through the same cycle of operation so that there is a condenser on charge for each incoming dot, and at the same time there is also one condenser in position II, and a third condenser is in the position of short circuit preparing itself for its next charge.

The resulting signal wave is applied to the control electrode 72 of the output tube 74. It will be noted that there is no grid leak resistor. This enables the condensers to hold their charge throughout the time interval as shown in Fig. 10.

Fig. 10 is a graphical illustration of the operation of the form of this invention shown in Fig. 9. During the dot portion of interval t_1 , t_2 condenser 71p is receiving its charge through the constant current device 65. This may be seen from the uniform slope of the dotted curve p. When the variable dot signal ceases during the time interval t_1 , t_2 the tube 65 is biased beyond cut-off so that the condenser 71p receives no further charge due to the fact that no current is flowing in the output circuit of the tube 65. It will be seen that during the no signal portion of time t_1 , t_2 , the dotted curve p maintains its amplitude and at time t_2 when the condenser 71p is changed to position II, the voltage across the condenser 71p is connected across the output circuit, and for the period t_2 , t_3 the output signal is equal to the voltage on the condenser 71p.

At time t_2 condenser 71r is connected to the charging circuit so that potential across 71r increases as represented by dash-dot line r during the signal interval of time t_2 , t_3 . Upon cessation of the variable dot signal, the tube 65 again is blocked causing the condenser 71r to maintain its voltage through the remainder of the dot interval t_2 , t_3 , and through the interval t_3 , t_4 during which time the condenser 71r is connected in the output circuit.

At time t_3 , the third condenser 71q does on charge. The potential of the condensers 71q is shown as dashed line q. As each of the condensers reach position III, they are discharged

and drop in potential immediately to the axis where they remain until they again assume position I to take on a charge for the next succeeding cycle of operation. It will be readily seen that by repeating this cycle of operation, a complete reconstructed signal wave will be produced.

Fig. 11 shows one form of this invention in which electronic means is used for switching rather than the mechanical means previously shown and described.

It will be noticed that two similar channels are provided for the conversion of a signal wave into a modulated dot signal and each channel works alternately.

A square wave generator 77 of any of the well-known types produces a push-pull square wave signal, such that its output voltage will vary suddenly between a predetermined positive potential and a predetermined negative potential.

A signal wave input is applied simultaneously to the control electrodes 79 and 80 of the discharge devices 81 and 82. Simultaneously, the output signal from the square wave generator is applied to an auxiliary electrode 83 of the discharge device 81 in a positive direction such that it causes the discharge device 81 to pass current. During the same interval that the positive potential is being applied to the auxiliary electrode 83, a negative potential is applied to the auxiliary electrode 84 of the discharge device 82 such that the current flowing through the discharge device 82 will be blocked. During this interval, a storage condenser 85 is receiving a charge which is proportional to the magnitude of the input signal by reason of the voltage drop through resistance 87 and discharge device 89 which has been made conducting during the time the discharge device 81 is drawing current.

During the next succeeding dot interval, the constant current device 91 is made conducting by reason of its auxiliary electrode 93 being connected to the output signal from the square wave generator, which is at a positive potential during the interval.

The charge which has accumulated on condenser 85 is prevented from leaking off through resistor 87 and tube 89 by reason of the tube 89 being made nonconductive during the interval that the constant current device 91 is made conducting. During this interval that constant current device 91 is made conducting the charging tube 81 is made non-conducting by the negative wave applied to its auxiliary electrode 83 by the square wave generator 77.

By reason of the fact that the constant current device 91 allows the charge on the condenser 85 to leak off therefrom at a uniform rate, the potential at the control electrode 95 decreases uniformly. It follows, in view of the phase reversing action of the discharge device 97, that the potential on the control electrode 99 of the gaseous discharge device 101, which is in a non-conducting state, increases in a positive direction during this uniform decrease of potential on the control electrode 95 of tube 97. When the potential on the control electrode 99 reaches a predetermined value, the tube 101 will become conducting. It will be clear that the length of time taken from the start of the discharge of condenser 85 to the instant at which the tube 101 is made conducting depends upon the amount of charge which the condenser 85 originally received by reason of the magnitude of the input signal at the instant when the condenser 85 was removed from the charging circuit and placed on

the discharging circuit by reason of the control voltage from the square wave generator.

During that time which the tube 101 is conducting, the potential on the control electrode 103 of the tube 105 is low, resulting in an accompanying high voltage on the anode 107 of the tube 105. This results in a modulated dot signal whose duration is dependent upon the time which the tube 101 is conducting.

Because of the fact that the gaseous discharge device must be extinguished, an auxiliary gaseous discharge device 109 is provided whose control electrode 111 is also connected to the square wave generator 77 such that the control electrode 111 will go positive to make the tube 109 conducting at the end of the interval during which tube 101 is conducting. The instantaneous pulse resulting from the tube 109 becoming conductive is impressed upon the output circuit of tube 101 through a coupling condenser 113 such that it produces a sufficient voltage drop in the output circuit of tube 101 to cause it to be extinguished by reason of the fact that, when the anode supply voltage of a gaseous discharge device drops below a predetermined amount, the gaseous discharge device is extinguished.

It will be seen that, at each succeeding dot interval, the channel is changed such that alternate dots of the modulated dot signals are produced by alternate use of the channels shown. The operation of the second channel is precisely the same as the operation of the first channel. It will be seen that this will produce a train of modulated dots, the duration of each dot of which is representative of the magnitude of the input signal at one of a set of predetermined, periodically recurring instants.

While several systems for carrying this invention into effect have been indicated and described, it will be apparent to one skilled in the art that this invention is by no means limited to the particular organizations shown and described, but that many modifications may be made without departing from the scope of this invention as set forth in the appended claims.

I claim as my invention:

1. In a signaling system, means for converting a signal wave into a train of variable dots reoccurring at a predetermined rate and wherein the duration of the dots is representative of the magnitude of said signal wave comprising in combination, means for sequentially charging each of a plurality of condensers at said rate and by an amount determined by the magnitude of said signaling wave, means for sequentially connecting each of said condensers to a constant current discharge device at said predetermined rate, and a discharge device connected to said constant current device whose conduction is controlled by the resulting potential across said constant current device.

2. In a signaling system, means for converting a periodically reoccurring variable dot train into a signal wave wherein the magnitude thereof is representative of the duration of the variable dots comprising in combination, means for sequentially changing the charge in each of a plurality of condensers at said rate and by an amount determined by the duration of said variable dots, a signal transmission circuit and means for sequentially connecting said condensers to said transmission circuit for controlling the production of a signal wave in said transmission circuit.

3. In a signaling system, means for converting a signal wave into a train of variable dots re-

occurring at a predetermined rate and wherein the duration of the dots is representative of the magnitude of said signal wave, comprising in combination means for sequentially charging each of a plurality of condensers at said rate and by an amount determined by the instantaneous magnitude of said signaling wave at instants reoccurring at said rate, means for sequentially connecting each of said condensers to a constant current discharge device at said predetermined rate, and a discharge device connected to said constant current device whose conduction is controlled by the resulting potential across said constant current device.

4. In a signaling system, means for converting a periodically reoccurring variable dot train into a signal wave wherein the magnitude thereof is representative of the duration of the variable dots comprising in combination means for sequentially changing the charge in each of a plurality of condensers at said rate and by an amount determined by the duration of said variable dots, a pair of constant current devices having input circuits and serially connected output circuits, means for sequentially connecting said condensers to each of said input circuits in a predetermined order and during each of the time intervals occupied by a variable dot.

5. In a signaling system, means for converting a signal wave into a train of variable dots reoccurring at a predetermined rate and wherein the duration of the dots is representative of the magnitude of said signal wave comprising in combination means for sequentially charging each of a plurality of condensers at said rate and by an amount determined by the magnitude of said signaling wave, means for sequentially connecting each of said condensers to a constant current discharge device at said predetermined rate, and means for controlling the period, and means for controlling the period of conduction in each of a plurality of gaseous discharge devices during predetermined intervals reoccurring at said periodic rate with the resulting potential across said constant current device during said interval.

6. In a signaling system, means for converting a signal wave into a train of variable dots reoccurring at a predetermined rate and wherein the duration of the dots is representative of the magnitude of said signal wave comprising in combination a pair of signal channels, means for alternately applying to each of said channels alternate dots of said variable dot train, each channel including a condenser, means for applying to said condenser a charge representative of the magnitude of said signal wave in the respective dot interval, a constant current device connected to said condenser, means for applying the potential across said constant current device to the input circuit of one of a pair of gaseous discharge devices whose output circuits are connected in parallel for controlling the ignition thereof, means connected to the input circuit of the other of said gaseous discharge devices for igniting the other of said gaseous discharge devices at the beginning of the respective dot interval to extinguish the first of said gaseous discharge devices, and a variable dot transmission channel connected to both of said signal channels for transmitting the resulting train of variable dots.

7. The method of signaling which comprises the steps of sequentially deriving individual electric charges proportional to the magnitude of a signaling wave, allowing the energy in each of the charges to be dissipated at a constant rate

and utilizing the charge to control the flow of current in each of a plurality of discharge devices sequentially to produce a train of periodically reoccurring dots whose duration is proportional to the magnitude of the said signal wave.

8. The method of signaling which comprises the steps of sequentially deriving individual electric charges proportional to the duration of the variable dots of a variable dot train and sequentially utilizing the charges to produce a signal wave whose magnitude is proportional to the duration of the variable dot train.

9. The method of signaling which comprises the steps of sequentially deriving individual electric charges proportional to the magnitude of a signaling wave, allowing the energy to be dissipated at a constant rate and utilizing said charge to control the ignition of each of a plurality of gaseous discharge devices sequentially to produce a train of periodically reoccurring dots whose duration is proportional to the magnitude of said signal wave.

10. The combination of a wave signaling apparatus including means for sequentially producing one plurality of electrical charges at a predetermined rate and of a magnitude dependent on the magnitude of said signaling wave, means for sequentially dissipating said charges at said predetermined rate, means responsive to said

charge dissipation for producing electrical pulses varying as the periods of said charge dissipation, wave signaling receiving apparatus including means for sequentially producing another plurality of electrical charges at said rate and of a magnitude determined by the duration of said pulses, and means sequentially responsive to said other electrical charges for reconstructing said signaling wave.

- 10 11. The combination of a wave signaling transmitting apparatus including means for sequentially charging one plurality of condensers at a predetermined rate and by an amount determined by the magnitude of the signaling wave, 15 means for sequentially connecting each of said condensers to a constant current discharge device at said predetermined rate, a discharge device responsive to the potential of said constant current device for producing electrical pulses varying as the potential of said constant current device, a wave signaling receiving apparatus including means for sequentially changing the charge in each of another plurality of condensers at said rate and by an amount determined by the duration of said pulses, and means sequentially responsive to the charges of said other electrical condensers for reconstructing said signaling wave.
